HINGE MOUNTING FOR SWINGING
CLOSURES

William M. Phelan, Montreal, Quebec, Canada

Application June 26, 1940, Serial No. 342,511

In Canada June 27, 1939
4 Claims. (Cl. 16—128)

This invention relates to improved means for hingedly mounting a door so that it is biased to assume a given position and to automatically return to that position whenever it is free to do so after being swung to a different position. The given position may be the closed or open position of the door.

More particularly, the invention consists in mounting a door by means of upper and lower hinges designed so that the upper and lower hinged portions of the door swing about relatively offset centers and describe arcuate paths of different radii. The construction and arrangement of the hinges is such that the door hangs true and level in a given position and, when swung from said position, is bodily slanted so that its own weight automatically causes it to return to said position whenever it is free to do so.

Proceeding now to a more detailed description reference will be had to the accompanying drawings, wherein—

Fig. 1 is an outside elevational view of a door mounted in accordance with my invention. In this view the door is shown hanging true and level in its closed position.

Fig. 2 is an inside elevational view of the door appearing in Fig. 1. In this view the door is shown in the slanted position which it assumes when open.

Fig. 3 is a top plan view of the door as it appears in the open position shown in Fig. 2.

Fig. 4 is a sectional view along the line 4—4 of Fig. 1.

Fig. 5 is a sectional view along the line 5—5 of Fig. 1.

Fig. 6 is a plan view of the door-carried leaf of the lower hinge appearing in the preceding figures.

Fig. 7 is a sectional view along the line 7—7 of Fig. 6.

Fig. 8 is an inverted plan view of the door-carried leaf of the upper hinge appearing in Figs. 1, 2 and 3.

Fig. 9 is a sectional view along the line 9—9 of Fig. 8.

Fig. 10 is a plan view of one of the post carried leaves of the hinges appearing in Figs. 1, 2 and 3.

Fig. 11 is a sectional view along the line 11—11 of Fig. 10.

In these drawings I have shown a door 5 hinged to a corner portion of a hollow rectangular door post 6 by upper and lower hinges generally indicated at 7 and 8. In this particular instance the hinges are so designed and arranged

that the door is biased to assume a closed position and to return to such position whenever it is free to do so after being swung to open position. When the door is in its closed position, the free vertical edge thereof engages a door stop carried by a second door post (not shown) located opposite the post 6. As the door swings to open or closed position the upper portion of the hinged edge swings about the centre C (Fig. 4) and describes the arcuate path P. The lower portion of the hinged edge simultaneously swings about the centre C' (Fig. 5) and describes the arcuate path P'. In its closed position the door hangs true and level as shown in Fig. 1. In its open position the door is bodily slanted (as shown in Fig. 2) by reason of the fact that the upper and lower portions of the hinged edge swing about the relatively offset centres C and C' and describes arcuate paths P and P' of different radii. It is this particular slanting of the door which causes it to swing back to a closed position by its own weight whenever it is free to so move after being opened.

As here shown the upper hinge 7 comprises a door-carried leaf 9 and a post-carried leaf 10. Leaf 9 is provided with a flat face 11 which is clamped against the outer side of door 5 by the threaded studs 12 and clamping nuts 13. Leaf 9 is also provided with a socket 14 in which is fitted an upwardly projecting pin 15 carried by the companion leaf 10. This pin and socket connection between the leaves 9 and 10 constitutes the hinge pivot, the centre of which is represented at C in Fig. 4. The hinge leaf 10 is notched to provide a right angle recess 16 defined by the walls 17 and 18. These walls 17 and 18 are respectively clamped against the faces 19 and 20 of the door post 6 by means of the threaded stud 21 and the clamping nut 22.

The lower hinge 8 comprises a door-carried leaf 24 provided with a flat face 25 which is clamped against the outer side of the door by the threaded studs 26 and the clamping nuts 27. This leaf 24 is also provided with a socket 28 in which is fitted a pin 15 projecting downwardly from the associated post-carried leaf 30. The leaf 30 is a duplicate of the previously mentioned post-carried leaf 10 except that it is reversely arranged so that the pin portion thereof projects downwardly instead of upwardly. In this connection it will be noted that leaf 30 is also provided with a right angle recess 16 defined by the walls 17 and 18. It will be noted, however, that the recess wall 17 of leaf 30 is engaged with the face 20 of post 6 while the recess wall 18 is en-

gaged with the post face 19. It is this reversal of the post-carried leaf 30 of the lower hinge with reference to the post-carried leaf 10 of the upper hinge which results in the hinge centre C' being offset relatively to the hinge centre C. It will also be noted that the door-carried leaf 24 of the lower hinge 8 is longer than the door-carried leaf 9 of the upper hinge. It is owing to this difference in the relative lengths of the door-carried hinge leaves and to the relative offsetting of the hinge centres C and C' that the door is caused to hang true and level in the closed position and to be bodily inclined when swung to the open position shown in Figs. 2 and 3.

The component parts of the hinges described herein are capable of interchangeable assembly so that they may be used for hinging the door to either the left or right hand post of a door opening and in such manner as to bias the door to assume either a closed or an open position. In the present drawings the door is shown hinged to the left hand door post. If it is desired to hinge the door to the right hand post this may be accomplished by applying the leaves of each hinge so that the relative positions thereof are reversed as compared with the present drawing. In other words, in the case of a door hinged to the right-hand door post so as to be automatically returned to closed position, the door-carried leaf 9 of the upper hinge would be inverted and arranged below the associated post-carried leaf 10, the latter being also inverted so that its pin 15 extends downwardly to fit within the upwardly facing socket of the inverted leaf 9. There would be a similar reversal of the leaves 24 and 30 of the lower hinge 8 so that leaf 24 would lie above instead of below its associated leaf 30. If it is desired to mount the door so that it tends to assume an open position and to automatically return to such open position after being closed this is accomplished by transposing the position of the two hinges so that the upper portion of the door is hung from the door post by the hinge 8 while the lower portion is hung by the hinge 7. This transposal of the hinges 7 and 8 is feasible whether the door is to be hinged to either the left or right hand door post.

The sockets 14 and 28 of the hinge leaves 9 and 24 are preferably fitted with suitable bushings 32 which serve as bearings for the hinge pins 15. These bushings may be made of graphite, metal or any other suitable material.

In the construction shown in Figs. 4 and 5 each stud 21 extends inwardly through a corner opening 34 of the post 6 and through a registering opening 35 of a filler piece 36 which is interposed between the nut 22 and the inner surfaces 37 and 38 of the two sides of the post which meet to form the corner to which the post-carried hinge leaves are applied. Each filler piece is provided with inclined surfaces 39 which are flatly engaged with the post surfaces 37 and 38 and with a further flat surface 40 against which the associated nut 22 is jammed as it is screwed home on the stud 21.

In Fig. 3 I have shown a slightly modified filler piece 36. In this case the filler piece is triangular in shape and completely fills the inside angle of the corner to which the post-carried hinge leaves are secured.

Having thus described what I now consider to be a preferred embodiment of this invention it will be understood that various modifications may be resorted to within the scope and spirit of the appended claims.

Having thus described my invention, what I claim is:

1. Means for hinging a door to a corner portion of a hollow rectangular post comprising upper and lower post-carried hinge leaves and upper and lower door-carried hinge leaves hingedly connected to said post-carried leaves, each of the last mentioned leaves being provided with a right angle recess in which the said corner portion of the post is fitted and with a threaded stud extending inwardly from the walls of said recess through an opening provided in the said corner portion of the post, a nut threaded on each of said studs and a filler piece interposed between each nut and the inner surfaces of the sides of the post which meet to form the aforesaid corner, said filler piece providing a flat bearing for said nut and being provided with inclined side surfaces disposed in flat engagement with the inner surfaces of the side walls of the post which form said corner, said filler piece being also provided with apertures through which said studs extend.

2. Means for hinging a door to a corner portion of a hollow rectangular door post so that the door is thereby biased to assume a given position and to automatically return to that position whenever it is free to do so after being swung to a different position, said means comprising upper and lower post-carried hinge leaves provided with right angle recesses in which the said corner portion of the post is fitted, said post-carried leaves extending outwardly at different angles from said corner portion, means for fastening said post-carried leaves to said post, upper and lower door-carried leaves of unequal length fastened to and projecting outwardly different distances from one side of said door, each door-carried leaf being provided with a vertical hinge pin which is fitted in a vertical socket of one of the post-carried leaves to provide a pivotal connection, the vertical axis of which is horizontally offset with respect to the vertical axis of the pivotal connection provided between the remaining post and door-carried leaves.

3. The construction set forth in claim 2 in which the means for fastening the post-carried leaves to said post comprises studs extending from the recessed portions of said leaves through corner openings provided in the said corner portion of the post and clamping nuts carried by said studs for clamping said leaves to said post.

4. The construction set forth in claim 2 in which the means for fastening the post-carried leaves to said post comprises studs extending from the recessed portions of said leaves through corner openings provided in the said corner portion of the post, clamping nuts threadedly engaged with the portions of the studs located within the post and filler pieces interposed between the clamping nuts and the post, said filler pieces being loosely mounted on said studs and being shaped to fit the inside angle of said corner portion.
